UNITED STATES PATENT OFFICE

WALTER GRUMBACHER, OF NEW YORK, N. Y.

ARTIST'S KIT

Application filed June 16, 1931. Serial No. 544,737.

My present invention relates generally to a combined artist's kit box and easel, and consists in the combinations and arrangements of parts hereinafter described, and 5 more fully set forth in the accompanying claims.

The invention has for its purpose to provide a new and improved arrangement for supporting a board upon which the sketch 10 is being made, and more particularly to the embodiment of this arrangement as part of an artist's kit.

For the attainment of this object and such other objects as may hereinafter appear or 15 be pointed out, I have illustrated embodiments of my invention in the drawings wherein:—

Figure 1 is a perspective view of my invention embodied in an artist's kit showing 20 the work panel supported in one position in full lines and another position in dotted lines;

Figure 2 is a face view of the cover member showing the bottom container in section; 25

Figure 3 is a longitudinal section through the artist kit in open position;

Figure 4 is a section taken on line 4—4 of Figure 3; and

Figure 5 shows a modification. 30 Upon viewing Figure 3 of the drawings, it will be observed that the artist kit in which my invention is illustrated is embodied, is made up of the bottom container member 10 to which is hinged the cover member 11 as 35 by the hinges 12, the brace 13 serving to secure the cover member in open position at predetermined inclinations or positions.

The base member 10 is provided with compartments for receiving the various instruments and has room immediately thereabove for receiving the palette 14. 40

My invention is illustrated and disclosed as embodied in the cover member of the artist kit. The cover member 11 is in the form of 45 a compartment, and is made up of a back 15, an upper end wall 16 and a lower end wall 17, and side walls 18 and 19. All of these walls have their upper surfaces in a common plane which will be hereinafter referred to 50 as the inner plane of the cover.

I will now describe my arrangement for carrying the paint board upon which the sketching is being done from the cover member, with its upper surface upon which the sketching is being done either in this common inner plane of the cover member or thereabove so that the artist when using the brush, for example, will have free movement of the brush even beyond the limits of the paint board. 55

The side walls 18 and 19 are provided with the opposed guiding and seating channels or grooves 25 and 26 each opening inwardly and upwardly and extending for the full length of the side walls. These channels or 60 grooves are normally closed at the top by the top wall 16, and always closed at the bottom by the bottom wall 17. These channels or 65 grooves each presents a bottom seat 27, and an end abutment wall 28, the bottom seats 70 27 of the channels 25 and 26 being in the same common plane and which will be hereinafter referred to as a seating plane of the sketching board, and the end guiding walls 28 being in parallelism. 75

The upper end wall 16 is provided with the upstanding backing or abutment members 29 (see Figure 3) and the bottom or lower end wall 17 is similarly provided with the upstanding backing supports 30. These 80 backing supports 29 and 30 are illustrated in the drawings as in the form of U-shaped brads, although they can take any preferred or desired form, provided, however, they are so constructed and positioned as to present 85 their outer surfaces in the seating plane i. e., same plane as that of the abutment seats or walls 27, and which forms the plane of the paint board seat, as will shortly be pointed out. 90

The upper end wall 16 is pivoted to the back wall 15 as shown at 35, so that it can swing from its normal full line position of Figures 2, 3, and 4 to its open position of Figure 1. 95

In Figure 1, I show the top wall 16 as thrown upwardly and out of the way. This opens the channels 25, and 26 at the top, and permits of the insertion of the paint board A in the following manner. The paint board is 100

brought into registration with the channels 25 and 26 with the lower surface in registration with the opposed seats 27 and the sides of the paint board in abutting relation to the end walls 28 and the paint board can then move downwardly along the cover to its final position as shown in Figure 1. In this operation, it will be guided by the seats 27 and by the end walls 28 until it strikes the lower end member 17. As it moves downwardly the board will position itself below or in back of the spring clips 36 and 37 carried by the side walls 18 and 19, and which extend over the grooves 25 and 26, and also in back of the spring clip 38 which is carried by the bottom end wall 17. These spring clips 36, 37 and 38 will serve to hold the board upon its seat. The board A will be guided to a position immediately in front of the backing members 30 in the lower end wall 17. These backing members have their upper or abutment surfaces in the plane of the seats 27. The cover member 16 is now brought down from its position of Figure 1 to its position of Figure 3, which will cause the members 29 carried by this top wall to position themselves in back of the upper end position of the board.

In this manner, the board when in its position of Figure 3 will rest at its sides upon the seats 27 and at its bottom against the brads 30, and at the top against the brads 29 and will be held from rising by the clips 36, 37 and 38. The board or panel A will be held stationary and will form a solid surface to paint against.

The depth of the grooves 25 and 26 will be substantially the same as the thickness of the board A, and the other dimensions of the board will correspond to the channel thus formed therefore. This will bring the upper surface of the board A in the common plane of the outer surfaces of the side walls, and the top and bottom end walls of the cover member so that these surfaces will form, in fact, a continuation of the top surface of the board A so that no impediment will be presented to the free sweep of the paint brush, and furthermore, to the use of the entire surface of the board for sketching purpose.

In this manner, the board A is supported and backed at various points and is also held down at other points so that the board will be held down against outward bulging and held flat against inward bulging.

For storage purposes, I show additionally the opposed sets of grooves 40' and 41 formed in the inner faces of the side walls 18 and 19 in which paint boards can be received for storage purposes, or even for painting purposes where the use of the entire surface of the board is not intended. In connection with these sets of grooves 40' and 41, it will be understood that the conformation thereof will not only seat the board, but will also hold a board against any upward movement.

The spring clips 36, 37 and 38 are illustrated in the drawings as preferably so mounted as to permit their being moved out of their inoperative position into an operative one and for this purpose are each mounted upon pivots 39 about which the clips can be swung from their overhanging full line position to their inoperative position. For holding each of these clips in any position to which they may be moved, I may employ the camming friction seat 39' shown in Figure 3.

My invention further contemplates an arrangement whereby the board instead of being positioned with its longer dimension horizontal as shown in Figure 1, can have its longer dimension positioned vertically, and as shown by dotted lines in the same figure of the drawing. In this position, the board A will be received, for example, in the groove on the right and beneath the right spring clip 37 and above the right brad 30 and beneath the lower clip 38, and for purposes of still further securing the board against movement when in this position, I have provided a member for engaging the left end of the board. This member is shown as in the form of the latch hook 40 pivoted on the underneath surface of the upper end wall 16, and limited in its swinging movement in a clock-wise direction, by the stop 42, so as to hold the latch in its extended position of Figure 1. The latch 40 is so positioned and dimensioned that, when in this extended position, it will present the open mouth 43 of its jaw, so that the left end of the board A can be received therewithin. It will, of course, be understood, that, in this position also, the board will be held in the common plane of the outer surfaces of the walls 17, 18 and 19, and that the wall 16 will be thrown about its pivot to its position as shown in Figure 1.

For securing a board upright and at the left, I may employ a hook 45 positioned similarly but oppositely to the hook 40 so that its jaw portion 46 will receive therewithin the right hand end of a board positioned on the left rather than on the right as shown in dotted lines in Figure 1 of the drawings.

Upon viewing Figures 1 and 2 of the drawings, it will be observed that the board A when supported as shown in Figure 2 and in its full line position of Figure 1 will be, when the top 11 is closed down upon the bottom 10, in full registration with and within the outlines of the chamber in the bottom member 10. In this manner, I attain the result of enabling a painter to close his kit box with the board secured as in Figure 1 without smudging or smearing the partly completed painting done on its outer surface. The artist, therefore, need not wait until his painting dries before packing up

and moving on. The clips 36, 37 and 38 serve additionally in this relationship.

In Figure 5 of the drawings, I show an alternative arrangement whereby I can attain the results referred to in the paragraph preceding. In this figure, the board A is received on the upper surfaces of the end walls 18 and 19 instead of on the seats 25 and 26 as shown in Figure 1. The clips 36' in this alternative form are secured to these upper surfaces as in Figure 1. The free ends 37' of the clips are, however, bent into a higher plane as shown in the drawings so as to permit these free ends to engage over the ends of the board as in Figure 1. The chambered portion 11' of the bottom member 11 is made sufficiently large so as to receive therewithin the board A as well as the bent ends of the clips. This has been shown in Figure 5.

Having thus described my invention, and illustrated its use, what I claim as new and desire to secure by Letters Patent is—

1. An artist kit comprising two sections forming a compartment therebetween, and hinged to each other so as to bring one of the sections at an angle to the other, one of said sections comprising a lower end wall, and a top end wall and two side walls, the outer surfaces of said side walls being substantially in a common plane, and means for holding a paint board flush with the outer surfaces of said side walls, and in said common plane, said means comprising channels in said side walls which are open outwardly.

2. An artist kit comprising two sections forming a compartment therebetween, and hinged to each other so as to bring one of the sections at an angle to the other, one of said sections comprising a lower end wall, and a top end wall and two side walls, the outer surfaces of said side walls being substantially in a common plane, and means for holding a paint board flush with the outer surfaces of said side walls, and in said common plane, said means comprising channels in said side walls which are open outwardly and means on said end walls serving as abutments for the ends of said board.

3. An artist kit comprising two sections forming a compartment therebetween, and hinged to each other so as to bring one of the sections at an angle to the other, one of said sections comprising a lower end wall, and a top end wall and two side walls, the outer surfaces of said side walls being substantially in a common plane, and means for holding a paint board flush with the outer surfaces of said side walls, and in said common plane, said means comprising channels in said side walls which are open outwardly, abutment members on the end walls for the ends of said boards, and members carried by said side walls and projecting over the channels and

substantially in said common plane for holding the board against an outward movement.

4. An artist kit comprising two sections forming a compartment therebetween and hinged to each other so as to bring one of the sections at an angle to the other, one of said sections comprising a bottom, a lower end wall, an upper end wall pivoted to said bottom, and two side walls, the outer surfaces of said side walls being of substantially in a common plane, and means for holding a paint board flush with the outer surfaces of said side walls, and in said common plane, said means comprising channels in said side walls extending for the full length of said side walls and open outwardly and closed at their upper ends when the pivoted upper end wall is in normal position and open when said upper end wall is swung out of its normal, and abutment means carried by said pivoted top wall, so arranged that when the upper end wall is moved about its pivot to its normal position, said abutment means will position themselves beneath a board received in said channels.

5. An artist kit comprising two sections forming a compartment therebetween and hinged to each other so as to bring one of the sections at an angle to the other, one of said sections comprising a bottom, a lower end wall, an upper end wall pivoted to said bottom, and two side walls, the outer surfaces of said side walls being of substantially in a common plane, and means for holding a paint board flush with the outer surfaces of said side walls, and in said common plane, said means comprising channels in said side walls extending for the full length of said side walls and open outwardly and closed at their upper ends when the pivoted upper end wall is in normal position and open when said upper end wall is swung out of its normal, and abutment means carried by said pivoted top wall, so arranged that when the upper end wall is moved about its pivot to its normal position, said abutment means will position themselves beneath a board received in said channels, and means on said lower end wall for buttressing the lower end of the paint board.

6. An artist kit comprising two sections forming a compartment therebetween and hinged to each other so as to bring one of the sections at an angle to the other, one of said sections comprising a bottom, a lower end wall, an upper end wall pivoted to said bottom, and two side walls, the outer surfaces of said side walls being of substantially in a common plane, and means for holding a paint board flush with the outer surfaces of said side walls, and in said common plane, said means comprising channels in said side walls extending for the full length of said side walls and open outwardly and closed at their upper ends when the pivoted upper end wall

is in normal position and open when said upper end wall is swung out of its normal means carried by said side walls and extending over and spaced above the bottom of said channels, and abutment means carried by said pivoted top wall, so arranged that when the upper end wall is moved about its pivot to its normal position, said abutment means will position themselves beneath a board received in said channels.

7. An artist kit comprising a compartment section and a hinged closure therefor, said closure being defined by a bottom, side walls, a top end wall and a bottom end wall; said top end wall being pivoted about the top of the bottom so as to be capable of assuming either its normal position or a position at an angle thereto, said side walls being provided with means for holding a paint-board flush with the outer surface of the side walls, so as to permit free movement of the brush for the full extent of the paint board.

8. An artist kit comprising two sections hinged to each other so as to permit of the section being held open at an angle to each other or in closed superimposed relation, one of said sections having a compartment therein and the other section comprising wall members and means for holding a paint board flush with the outer surface of said other section, said holding means being so constructed and arranged that a board held thereby will register with and being received within the outlines of the compartment of the first mentioned member, so that the kit can be closed without marring the paint on the board.

In witness whereof I have hereunto signed my name.

40 WALTER GRUMBACHER.
